GAS LIFT APPARATUS

Thomas E. Bryan, Fort Worth, Tex.

Application August 3, 1939, Serial No. 288,191

6 Claims. (Cl. 103—232)

This invention relates to gas lift apparatus and has particular reference to mechanism for operating and controlling the flow of oil wells.

An object of the invention is to provide a valve unit which may be operated from the earth's surface and may be installed and removed without pulling the well tubing.

Another object of the invention is to provide a setting and jarring member whereby the valve unit may be securely seated in operative position and subsequently removed without the necessity of using separate sets of tools for the installation and removal operations.

Still another object of the invention is to provide a wire line valve which may be removed from its seat in a well tubing without cutting the line, as required when using a fishing tool.

A further object of the invention is to provide a valve unit at the lower end of a wire line or cable which may be converted to various uses, such as a pressure differential valve, according to the requirements determined by the well conditions.

Other objects and advantages will be become apparent from the following description of the accompanying drawings, wherein:

Figure 1 is a diagrammatic view of a well showing features of the present invention embodied therein.

Figure 2 is a vertical sectional view of the valve receiving assembly which is designed for attachment to the tubing of the well and shows the valve unit positioned therein.

Figure 3 is a vertical sectional view of one form of the jar tool attached to the upper end of the stem of the valve unit.

Figure 4 is a vertical sectional view of the valve assembly, and showing the form of the invention which has piston type valve elements.

Figure 5 is a vertical sectional view of a below packer installation.

Figure 6 is similar to Figure 4, but illustrates a modified form of valve elements.

Figure 7 is a vertical sectional view of a modified form of a jar tool showing the rod member in elevation.

Figure 8 is similar to Figure 7, but is showing the rod removed.

Figure 9 is a vertical sectional view of a type of kick-off valve which may be installed in the tubing above the normal operative position of the valve unit.

Figure 10 is a vertical sectional view of the wire line actuating cylinder.

Figure 11 is taken on lines 11—11 of Figure 5. 55

Figure 12 is taken on lines 12—12 of Figure 6.

Figure 13 is a diagrammatic view of a modified form of the wire line actuating mechanism, and Figure 14 is taken on lines 14—14 of Figure 13.

In the drawings, the numeral 1 generally designates a well comprised of a casing 2 having a head 3 for hermetically sealing and supporting a string of well tubing 4. At the upper end of the tubing 4 there is mounted a cap 5 having a stuffing box 6 in the upper end for slidably receiving a wire line or cable 7. Above the head 3 and connected to the tubing 4, there is a discharge pipe 8 which is controlled by a gate valve 9, and intermediate the said discharge pipe 15 and the cap 5 there is connected in the tubing 4 another gate valve 10 for closing the said tubing when the cap 5 and wire line 7 are removed.

Kick-off valves 11 are positioned at intervals 20 in the tubing 4, and may be of any conventional construction, but are preferably of the double seat type as shown in Figure 9. Each of the double seat valves 11 referred to includes a housing 12 integral and within the side of the tubing connecting castings 13. A gas inlet is provided in the housing 12 for communicating gas through the valve 11 and into the tubing 4. This type of valve is well known to the art, and therefore a detailed description of the valve elements is unnecessary in the present disclosure.

Between the casing 2 and the tubing 4 there is positioned a packer 15 which is normally below the static level of the oil. Above the packer 15 and below the lowermost kick-off valve 11 there is connected in the tubing 4 a cylindrical housing 16 of relatively large diameter, as particularly shown in Figure 2. Concentrically mounted within the housing 16 and spaced from the inner walls thereof, by rigidly attached rods 40 17, there is positioned a valve receiving and retaining sleeve 18. Laterally positioned conduits 19, as particularly shown in Figure 2, are provided for gas passage between the interior of the sleeve 18 and the exterior of the housing 16.

At the upper end of the tubing 4 and below the stuffing box 5 there is a bracket 20 which supports a freely rotatable pulley 21. The bracket 20 also supports a cylinder 22 as shown in Figure 1, which contains a piston 23 which is connected to the wire line 7 by means of a threaded coupling 24 attached to the upper end of the piston rod 25, as shown in Figures 1 and 10. A cap 26 encloses the upper end of the cylinder 22 and is provided with a stuffing box 27 for slidably engaging the piston rod 25.

Connected to the lower end of the wire line 7 in the tubing 4 there is a valve unit 28 which is operatively received within the sleeve 18, previously referred to. The unit 28 includes a housing comprised of a body 29, and upper and lower caps 30 and 31 connected thereto by upper and lower sleeves 32 and 33. Rings 34 and cups 35 are mounted on each of these sleeves for providing a seal with the ends interior of the valve receiving sleeve 18. Intermediate the ends of the body 29 there is a threadedly attached member 36 which has a cylindrical bore through its center. There are vertical passages 36' around the central bore, the same being shown in dotted lines in Figures 4 and 6, and more particularly shown in Figure 12. Lateral openings or inlets 37 are formed in the cylindrical member 36 so as to receive gas pressure from the conduits 19 of the cylindrical housing 16.

The upper cap 30 of the valve unit 28 is provided with a hollow fishing neck 38 through which extends a valve stem 39. The fishing neck 38 provides a means of retrieving the unit 28 if the line 7 should break or otherwise become inoperative. In the form of the invention shown in Figure 4 the stem 39 has pistons 40 and 41 thereon above and below the inlets 37. The inner diameter of the upper sleeve 32 is of greater diameter than the upper piston 40 so as to provide for the passage of gas when the stem 39 is in a raised position. The gas may then be conducted through the upper sleeve 32 and thence through openings 42 in the upper cap 30 to the interior of the tubing 4. Other openings 42' are formed in the lower cap 31 for allowing passage of oil through the vertical passages 36' of the member 36.

A standing valve 43 positioned in the tubing 4 below the housing 16 prevents the oil from being forced downward when the valve unit 28 is opened.

To open and close the valve 28 there is a jar rod unit 44 for operating the upper end of the valve stem 39. Two forms of jar rods are illustrated in the drawings, and are substantially the same in construction, as will be seen. The jar rod illustrated in Figure 3 is comprised of a tubular body 45, and has a rod 46 slidably positioned therein. The lower end of the rod 46 is in the form of a projection for engaging a constricted portion at the upper end of the tubular body 45. There are openings 47 in the upper and lower ends of the body for relieving any pressure which might otherwise hinder the jarring action when setting or retrieving the valve 28. The lower end of this form of jar rod unit is threaded to the upper end of the valve stem 39, and thus, after the valve 28 is set in the sleeve 18, the rod 46, which is connected at its upper end to the line 7 by a coupling 48, may be raised until the stem 39 is caused to open the said valve. By slightly raising and lowering the line 7, the well will be caused to flow, provided there is sufficient gas pressure within the casing 2.

To operate the piston 23, a motor valve 49 is provided at the earth's surface, the discharge of which is connected to the cylinder cap 26 by a conduit 50. Another conduit 51 supplies gas pressure for this connection, but before passing through the motor valve 49, the pressure is branched by a T 52 to the diaphragm 53 of the said motor valve. A gate valve 54 and a time cycle device 55 are connected in the conduit 56 between the diaphragm 53 and the T 52. The purpose of the time cycle device 55 is to inter-

mittently supply gas pressure against the diaphragm 53 for opening and closing the motor valve 49, and the purpose of the gate valve is to regulate the amount of pressure exerted against the said diaphragm.

It is to be understood in operation, the intermitting or time cycle device has an automatic pressure release in the line carrying gas pressure to the top of the motor valve 49, whereby, after each cycle, upon closing, the time cycle device automatically releases the gas pressure effective on the diaphragm of the motor, so that said motor valve returns to closed position. Likewise in the operation of the apparatus employing the piston and cylinder 22, after each operation of the time cycle device, the gas pressure employed to operate the piston downwardly, is slowly allowed to escape thru the stuffing box 27, so that the return of the line downwardly is slowly controlled.

The time cycle device 55 and the motor valve 49 may be of conventional constructions and are therefore not described in detail.

A modification of the valve unit 28 is shown in Figure 6 and includes the body 29, the fishing neck 38, the upper and lower caps 30 and 31, the openings 42 and 42' therein, the sleeves 32 and 33, rings 34 and cups 35, as well as the cylindrical member 36 having the vertical openings 36' around the central bore, and the inlets 37, all as previously described. The stem 60 differs in that its upper end is not threaded, and is acted upon in a manner to be described. In place of the pistons 40 and 41, a conical valve element 61 is provided to move upwardly to engage a seat 62 in the member 36 above the inlets 37. Similarly, there is a smaller conical valve element 63 positioned on the stem 60 below the inlets 37. The latter named element 63 likewise seats upwardly against a seat 64. Since the upper element 61 is the larger, and by reason of the direction of the seating, pressure from the casing 2 normally causes the unit 28 to be closed and to extend the stem 60 beyond the neck 38. By this construction a valve is provided which will close against the weight of the valve operating elements of the jar when velocity of flow becomes excessive, and thus prevents the unit from being blown from the retaining sleeve 18.

A modified form of the jar rod is illustrated in Figure 7 and is designed to impart the downward force necessary for the operation of the form of valve illustrated in Figure 6 and described above. This form of jar includes a tubular body 65 having opposingly positioned slots 66 intermediate the ends. (See Figure 5 as well as Figures 7 and 8.) The lower end of the body 65 has a threaded nipple 67 which is designed to enclose the upper end of the fishing neck 38. Bolts 68 through the nipple 67 secure the neck 38 in place. A rod 69, having threads at the upper end for connection to the coupling 48 and the wire line 7, extends into the body 65 and has integral projecting lugs 70 near the lower end for slidably engaging the slots 66. The lugs 70 are so positioned as to allow the lower end of the rod 69 to force the stem 60 down when the line is lowered and the valve 28 has been installed.

Either of the forms of the valves referred to may be employed in the below packer assembly illustrated in Figure 5. The housing 71 shown is substantially longer than the housing 16 previously referred to. A packer 72 is positioned between the housing 71 and the casing 2. The tubing 4 is connected to and extends downwardly

into the said housing and has at its lower end a valve seating means such as a ring 73, as shown in section in Figure 5. A seal 74 is positioned between the housing 71 and the tubing 4, as particularly shown in Figures 5 and 11.

When the valve unit 28 is set in operative position, gas pressure is conducted from the casing 2 through ports 75 in the housing 71 above the packer 12, thence through conduits 76 which extend downwardly through the seal 74 and into the tubing 4 in the proximity of the operative position of the valve inlets 37. Other ports 75' are provided in the tubing 4 below the seal 74 for allowing oil to enter the upper part of the said tubing when the oil is rising to its static level. The lower end of the housing 71 may be swaged or otherwise constricted. At the lower end of the housing 71, or in the lower tubing 77, there is positioned a standing valve 78 for maintaining the oil in the said housing and the upper tubing 4.

Another form of wire line actuating mechanism is illustrated in Figures 13 and 14 and includes the cap 5 and the stuffing box 6 connected to the top of the tubing 4, the pulley 21, and a pulley supporting bracket 79. A time cycle device 55, as previously referred to, is employed for the purpose of intermittently exerting gas pressure against a diaphragm 80 which forms a resilient partition in a bell housing 81. A conduit 82 is operatively connected between these parts as shown in Figure 13. A tubular member 83 is attached to the lower end of the bell housing 81 and has longitudinal slots 84 and 85 in opposing sides thereof. On each side of one of the slots 85 there is a laterally extending pair of spaced arms 86 which pivotally receive a lever 87 by means of a bolt 89. A rod 90 extends through the tubular body 83 and is attached at one end to the diaphragm 80. The lever 87 is connected to the rod 90 by a pin or bolt 91 and guides 92 are positioned in the upper and lower ends of the body 83 to prevent lateral movement of the rod 90. The wire line 7, which extends from the stuffing-box 6 and over the pulley 21, is connected to the outer end of the lever 87.

Holes 94 in the arms 86, and corresponding holes 95 in the lever 87, provide adjustment for the movement of the wire line 7 since the bolts 89 and 91 may be inserted at different distances with respect to each other.

In lowering or withdrawing the valve unit 28 in the tubing 4, the line 7 may be connected to a reel 96 or similar device at the earth's surface. Thus, the valve 28 may be set or dislodged by the jarring action of the unit 44, and, when the tubing cap 5 is removed, the said unit may be inserted in or removed from the tubing 4.

To aid in the retaining of the valve 28 in operative position, a latch 97 of the shear pin type may be attached to the lower and outer edge of the lower valve cap 3 for engaging an annular groove 98, such as shown in Figure 2.

If the static level of the oil reaches or extends above any of the kick-off valves 11 in sufficient quantities to open the same, the wire line operated unit 28 may be caused to remain idle until the well has become so depleted as to render the said kick-off valves ineffective. Obviously, the combined use of the operated unit 28 and the kick-off valves 11 will provide an efficient means of flowing a well with a relatively low gas pressure.

The valve unit 28 may be operated in any type

10 tubing without a housing provided the said tubing has seating means and gas passages to the valve inlets 37. In such an arrangement the oil will pass through the lower cap openings 42' and the vertical passages 36' in the member 36. When the unit is operated in either of the described housings 16 or 71, these last referred to openings and passages may be eliminated since the rising oil will pass around either of the described valve retaining means.

15 This application is a continuation-in-part of my co-pending application, Serial No. 255,395.

What I claim is:

1. In a wire line operated valve unit comprising a housing capable of being lowered into a well tubing and operably located adjacent the lower end thereof which has gas passage means through the wall thereof, the combination of a well tubing, a housing, a stem within the said housing and extending through the upper end thereof, inlets in the said housing for receiving gas from the said passage means in the said tubing, passages extending from the said inlets through the said housing, valve elements on the said stem for opening and closing the said inlets, a tubular body attached to the upper end of the said housing and around the said stem, a rod slidably mounted within the said tubular body and adapted to operate the said stem, a wire line attached to said rod and extending to the surface of the well through said tubing.

2. In a wire line operated valve capable of being lowered into a well tubing which has gas passage means through the wall thereof, the combination of a well tubing, a housing positioned within said tubing near its lower end, a stem within the housing and extending through the upper end thereof, inlets in the said housing for receiving gas from the said passage means in the said tubing, passages extending from the said inlets through the ends of the said housing, valve seats in the said housing above and below the said inlets, valve elements on the said stem for engaging the said seats, a tubular body attached to the upper end of the said housing and around the said stem, a rod capable of contacting and operating the said stem and slidably mounted in the said tubular body, and a vertically operated wire line extending through the said tubing and connected to the said rod.

3. A gas controlling valve mounted within a well tubing adjacent the lower end thereof, said valve comprising a tubular valve housing with a reduced head portion, a valve within said housing for controlling passage of pressure fluid therethrough, ports through the walls of said housing providing pressure fluid inlets to the interior of said valve, ports in the wall of the well tubing in registration with the said above ports, having communication exteriorly the said tubing, pressure fluid exit communications interiorly the said valve communicating with the interior of the well tubing, a portion of said valve extending into the reduced portion of said housing, a telescopic tool associated with said extending portion of said valve, a wire line attached to one end of said telescopic tool and extending to the well's surface through said tubing, for inserting or removing said valve housing into or from said well tubing, and means at the well's surface controlling the movement of said wire line.

4. A gas controlling valve mounted within a fitting attached to a well tubing adjacent the

75

lower end thereof, comprising a tubular valve housing with an interiorly bored reduced head portion, a vertically movable valve stem within said housing for controlling entrance of pressure gas into said well tubing, communications exteriorly said fitting to the interior thereof, communication ports in said valve housing registering with said above communications and pressure gas exit communications from said valve housing to the interior of said well tubing, a portion of said valve extending into and through said reduced portion of the valve housing, a telescopic tool associated with the extending portion of the valve within the said reduced head of the housing, a wire line attached to the upper end of said telescopic tool and extending upwardly through the said tubing to the well's surface for raising or lowering said telescopic tool and extending portion of the said valve thereby controlling movement of said valve.

5. In a valve structure mounted in the lower end of a well tubing controlling entrance of pressure gas into said tubing, the combination of a well tubing and a fitting threadedly attached thereto at either end, said fitting comprising a valve receiving chamber, passages for the uninterrupted flow of well fluid therearound, ports in said fitting, affording communication from its interior to the exterior thereof, a valve housing removably mounted within said fitting, a gas controlling valve within said last housing, a port in said valve affording communications with first named ports, outlets from said valve interiorly said valve housing, vertical fluid passages associated with the exterior of said valve affording uninterrupted well fluid passages around said valve within said valve housing, communications from said valve housing at either end, communicating with the interior of said well tubing, means to admit well fluid into the lower end of said well tubing, means to prevent the back flow of pressure fluid into the well, an extending part

10 of said gas controlling valve slidably operable through the head portion of said valve housing, a telescopic tool operatively attached to the said valve, a wire line attached to one end of said telescopic tool and extending interiorly the said tubing, to the well's surface, a stuffing gland on the upper end of the said tubing affording gas tight passage of the said wire line, a cylinder and piston associated with said line, means to alternately raise or lower said line by movement of said piston thereby operating the gas controlling valve in the well tubing.

15 6. In a gas controlling valve for injecting pressure gas into the tubing of an oil well for ejecting the oil therefrom, a removable valve unit comprising a valve housing, a valve, controlling passage of pressure gas therethrough, a sliding sectional tool connected with said valve, a wire line connected to one end of said tool and extending to the well's surface interiorly of the said tubing, for controlling operation of the said valve attached to the lower end of the sectional tool, a port in said valve housing for registration with said above port, ports in said valve communicating with said above ports affording communication with the tubing, means to secure said valve housing at a predetermined point in the interior of said tubing, means to dislodge said valve housing from association with the interior of the well tubing, means associated with the said wire line at the well's surface for actuating said line, tool and valve for controlling passage of gas into said well tubing at the lower end thereof, means independent of said last means for withdrawing said line, tool and valve housing from the well tubing, fluid passages vertically surrounding said valve for the entrance of well fluid into said well tubing at full capacity of well.

20 25 30 35 40 THOMAS E. BRYAN.
